UNITED STATES PATENT OFFICE.

WILLIAM F. HUTCHINSON, OF BOUND BROOK, NEW JERSEY, ASSIGNOR TO
HIMSELF AND THE OLIVER WIRE COMPANY, OF PENNSYLVANIA.

WIRE-NAIL MACHINE.

SPECIFICATION forming part of Letters Patent No. 593,020, dated November 2, 1897.

Application filed November 5, 1896. Serial No. 611,099. (No model.)

To all whom it may concern:

Be it known that I, WILLIAM F. HUTCHINSON, of Bound Brook, in the county of Somerset and State of New Jersey, have invented
5 certain new and useful Improvements in
Wire-Nail Machines, of which the following
is a full, clear, and exact description.

My invention relates to improvements in
rotary machines for cutting nails from a
10 continuous wire; and the object of my invention
is to produce a simple and durable machine
of this character which has a system of
rotary cutters adapted at one operation to cut
a perfect nail-point, to provide an intermit-
15 tently-operating clutch by which the wire is
held rigidly while the point is cut, and to pro-
duce a heading device operating automatically
after the cutting of the nail-points to
form the heads on the several nails, all to the
20 end that perfect nails may be rapidly made.

To this end my invention consists of a nail-
machine the construction, organization, and
operation of which will be hereinafter fully
described and claimed.

25 Reference is to be had to the accompanying
drawings, forming a part of this specification,
in which similar figures of reference indicate
corresponding parts in all the views.

Figure 1 is a broken sectional plan on the
30 line 11 of Fig. 2 of the machine embodying my
invention. Fig. 2 is a vertical section on the
line 2 2 of Fig. 3. Fig. 3 is a broken sectional
side elevation of the machine. Fig. 4 is an
enlarged detail view, partly in section, of the
35 cutters and the feed-clutch. Fig. 5 is a detail
face view of one of the cutting-rolls and the
cutters thereon. Fig. 6 is an enlarged detail
sectional view of one of the nail clamps or
jaws and the arrangement for heading the
40 nail while it is held in the jaws, and Fig. 7 is
a detail plan view of the nail-guide which re-
ceives the nail-blank as it comes from the
cutters and guides it to the carrying-jaws
which hold the blank until the nail is headed.

45 The machine has a frame 10 substantially
constructed and of any preferred design, at
the top of which is a suitable guide 11, through
which guide is fed the wire 12, from which the
nail is cut. From the guide 11 the wire
50 passes between feed-rolls 13, which also assist
in straightening the wire, these rolls being

carried by shafts 14, journaled on the frame-
top and geared together by gear-wheels 15,
one of which is driven from an idler 16,
which is driven by a gear-wheel 17, the latter 55
meshing with a gear-wheel 18, which in turn
is driven by one of a pair of gear-wheels 20
on the shaft of the cutter-rolls, to be herein-
after described. The gear-wheel 17 is on a
shaft 19, to be hereinafter referred to. This 60
shaft has also a beveled pinion 21 meshing
with a beveled pinion 22 (see Fig. 2) on a
shaft 23, the latter being driven by a pinion
24, which through the medium of an idler 25
is driven by a gear-wheel 26 on the shaft 27, 65
and the gear-wheel 26 is driven from a pinion
28 on the main driving-shaft 29, which has a
suitable driving-pulley 30. It will of course
be understood that any suitable driving mech-
anism may be used for driving the parts of 70
the machine; but I have referred to the above
gears in order that the operation may be un-
derstood, and some of the parts will be more
specifically referred to below.

After leaving the feed-rolls 13 the wire 12 75
passes through the feed-clutch 31, which oper-
ates intermittently, closing on the wire while
the latter is being severed and the nail-point
formed, as below described, and opening to
permit the feed of the wire. This clutch 31 80
has a stationary part 32, which is screwed
into the frame, and is therefore adjustable,
being held by a lock-nut 33, (see Fig. 2,) and
opposite the part 32 is a sliding portion 34,
which moves in a suitable bearing and which 85
connects with the part 32 by means of dowel-
pins 35, (see Fig. 4,) there being two pins which
straddle the wire, although the figure illus-
trates but one. The clutch is normally pressed
open by the spiral springs 36, which encircle 90
the dowel-pins. The outer end of the sliding
part 34 is preferably reduced, as shown as 37,
and this part is struck successively by the
rolls 38, which are journaled on the wheel 39,
this being carried by the shaft 19 already re- 95
ferred to, and the shaft is timed so that a roll
38 will strike the reduced end 37 of the part
34 of the clutch 31 and close the clutch on the
wire 12 at the same instant that a nail-point
is being cut below the clutch, and thus the 100
wire is held firmly, so that a perfect point can
be made.

The wire is severed to form nail-blanks and the points cut by the cutter-rolls 40, which turn opposite each other and are arranged below the clutch 31, these rolls being carried by shafts 41, which shafts are driven by the gear-wheels 20, described above. Each cutter-roll has a groove 42 on its face (see Fig. 5) to receive and guide the wire, and the face of each roll is also recessed at regular intervals, as shown at 43, in which recesses are placed the slightly-oscillating cutters 44, which are arranged in pairs and have opposite bits 45 adapted to close upon the wire and cut obliquely downward into it, as will be more specifically described presently. Each pair of cutters has a split shank 46 with a suitable shoulder 47 thereon turning in a recess of the roll 40, the shank being cut away slightly from the center to one edge to provide for a limited oscillation, as shown clearly in Fig. 5. The shanks 46 are grooved at the inner end, as shown at 48 in Fig. 4, to receive wedge-pins 49, which prevent the accidental displacement of the shanks and cutters. Any suitable means, however, can be used to hold the cutters in place, and the invention is not limited to the particular cutters shown. Each cutter 44 is provided on the outer edge (see Fig. 5) with shoulders 50 and 51, which successively engage fixed abutments 52, which are secured to the frame of the machine and which are arranged opposite each cutter of a pair, so that as the roll 40 advances the abutments first strike the shoulders 50 and close the bits 45 upon the wire, this closure being gradual by reason of the inclined shape of the abutments, and as the shoulders 51 are behind the center of the cutters this causes the cutters to be again opened to engage the wire after a revolution of the roll 40.

By reference to Fig. 4 it will be understood that the rolls 40 are timed so that opposite pairs of cutters approach opposite sides of the wire 12 simultaneously, and hence each pair of cutters will at the same instant engage the wire and be gradually forced into it by the abutments 52 and will also move downward by the motion of the rolls 40, so that a point 12^a is cut on the wire, while the upper end of the blank 12^c below the point will be whiskered or prolonged, as shown at 12^b in Fig. 4, and these whiskers when the nail is headed are welded with sufficient nicety to form a good head, and therefore no material is wasted. This is an important matter, as usually the part corresponding to the whiskers or prongs is cut off, and the waste amounts to from two and one-half to three per cent. of the material in the nails.

After leaving the cutter-rolls 40 the blanks 12^c are dropped into the guide 53, which is shown in detail in Fig. 7, and which has parallel and meeting blocks or plates 54, with a hole 55 therein to receive the nail-blank. These plates are separable, being fixed to spring-arms 56, which are secured to a suit-

able head or block 57 on the bolt 58, which can be fastened to the frame of the machine, as shown in Fig. 3. Any spring-guide of the general character described may be substituted for the one shown without affecting the principle of the invention.

The guide 53 serves to guide the nail-blanks 12^c to the clamping-jaws 59 and 60 on the rotary wheel or carrier 61, which is secured to the shaft 27, already referred to and shown clearly in Fig. 2. Of these jaws the jaw 59 is fixed and the jaw 60 slideable in and out in relation to the fixed jaw, so that the nail-blank can be clamped securely between them, and the parts next the nail are of course suitably hardened. The periphery or face of the wheel 61 is grooved, as shown at 62, so that the nail-blank can enter the groove and be guided to the jaws before it leaves the guide 53, and after it is clamped by the jaws the motion of the carrier or wheel 61 pulls the blank from the guide 53. Each jaw 60 is notched, as shown at 63, to receive the free end of a spring 64, (see Fig. 6,) which is fastened to the wheel or carrier 61, and the tension of which closes the jaw, and the jaw has also at its outer side and inner edge a lip 65, which engages a segmental guide 66, (see Figs. 2 and 3,) carried by springs 67, and this guide 66 by pressing on the lip 65 holds the jaw 60 open, as shown at the bottom of Fig. 2, so that the nail-blank can drop between the two jaws; but as soon as the lip 65 leaves the guide 66 the spring 64 closes the jaw 60 against the nail-blank sufficiently to hold the blank in place, but the jaw is more securely held when the blank is headed, as hereinafter described. When the jaws are finally forced firmly against the nail-blank, the latter is barbed, the jaws being provided with dies 68 for this purpose. No invention is claimed for this arrangement, and the dies can be made of any length and located at any desired point with reference to the nail.

As the carrier or wheel 61 revolves the outer ends of the nail-blanks 12^c pass beneath a presser-plate 69, which gradually approaches the carrier, and so the nail-blanks are pressed well into the jaws 59 and 60 until only a sufficient part of a blank protrudes to form a suitable head.

The heading is done by the plungers 70, which are forced, as presently described, against the protruding ends of the nail-blanks, and each pair of jaws 59 and 60 is slightly recessed around the part which receives the blank, in which recess the head is formed, as shown clearly in Fig. 6. At the time the blank is struck by one of the plungers 70, as shown in Figs. 1 and 6, the jaw 60, holding the particular blank which is being headed, is forced rigidly against the blank by an abutment-roller 71, although a cam-abutment can be substituted, if preferred, the roller being journaled on a suitable supporting bracket 72.

The plungers 70 are arranged near the periphery of a rotary carrier 73 and move parallel with the axis of the carrier. The carrier is secured to a shaft 74, which is driven by a beveled pinion 75, meshing with the beveled gear-wheel 76 on the shaft 27. The plungers 70 are arranged so as to register with the ends of the nail-blanks brought along by the jaws 59 and 60, and the plungers are successively thrown forward by the rolls 77 on the wheel 78, the latter being revolved by a shaft 79, which is journaled on the machine-frame and driven by a gear-wheel 80, which by means of an idler 81 engages the gear-wheel 26 on the shaft 27. When the roll 77 strikes a plunger, it throws the latter violently forward, and the plunger strikes the protruding pronged end 12^b of the nail-blank 12^c and rams the said end into the recess at the outer end 20 of the jaws 59 and 60, thus welding the prongs and making a head.

As the wire 12 is fed into the machine by the rolls 13 and through the clutch 31 the latter is closed intermittently upon the wire at 25 the time that the wire is cut by the rotary dies or cutters 44 of the cutting-rolls 40. The feed of the machine is continuous, however, as the wire is stopped by the clutch 31 only for the slightest instant, and this merely 30 causes the wire to buckle between the clutch and the feed-rolls. As soon as the wire is cut and the point formed by the cutters 44 the wire straightens out ready to be cut again. As fast as the blanks are cut off by the cutters 44 they are dropped one by one into the 35 guide 53 and between the jaws 59 and 60 of the wheel or carrier 61, which close, as already described, upon the nail-blanks, and the blanks when carried forward by the wheel 40 are pulled from the guide 53, forced inward by the presser-plate 69, headed by the plungers 70, all acting in detail, as already specified, and, finally, after leaving the plungers 45 the jaws 60 are reengaged by the guide 66 and opened, so as to release and drop the complete nails.

It will be understood that in this machine and the one described in another application filed simultaneously herewith the feed is 50 constant and continuous, and that the wire is rapidly cut by a rotary system of dies and cutters into nails. This enables the work to be done with the utmost rapidity and is, therefore, a very important feature of the 55 invention.

Having thus described my invention, I

claim as new and desire to secure by Letters Patent—

1. In a nail-machine, the combination of the oppositely-arranged cutter-rolls, each roll 60 having on its face oscillating knives shaped and actuated so as to cut two sides of a nail-point, substantially as described.

2. In a nail-machine, the combination of the oppositely-arranged cutter-rolls having 65 recessed faces with oscillating knives in the said recesses, the knives being arranged in pairs and the opposite pairs being shaped and actuated so as to cut the four sides of a nail-point, substantially as described. 70

3. In a nail-machine, the wire-clutch comprising oppositely-arranged parts movable in relation to each other and arranged to permit the passage of a wire between them, a guide entering the ends of the opposite parts to 75 make them register, and movable abutments adapted intermittently to strike one of said parts, substantially as described.

4. In a nail-machine, the combination with 80 a cutter-roll and the oscillating knives having shoulders on their outer edges, of the abutments in the paths of such shoulders, substantially as described.

5. In a nail-machine, the combination of the oppositely-arranged cutter-rolls, and the 85 oscillating knives mounted in pairs on the rolls, means for closing said knives gradually on a wire between the rolls and open the same as the wire is passed, substantially as described. 90

6. In a nail-machine, the nail-blank carrier comprising a rotary wheel having opening and closing spring-actuated jaws on its face and a peripheral guide-slot extending between the open jaws, an abutment to move 95 the jaws against the tension of the spring, and a presser-plate arranged opposite the jaws and adapted to press nail-blanks between the jaws, substantially as described.

7. In a nail-machine, the combination with 100 the rotary carrier, of the jaws arranged in pairs on its face, one jaw of each pair being fixed and the other slidably in relation to the fixed jaw, a spring closure for the slidably jaw, and means, as the segmental guide and 105 the lip on the jaw, to move the latter against the tension of the spring, substantially as described.
